UNITED STATES PATENT OFFICE.

ROBERT LEYER, OF GUMMERSBACH, GERMANY.

RECTIFIER FOR SPIRIT-STILLS.

SPECIFICATION forming part of Letters Patent No. 689,010, dated December 17, 1901.

Application filed July 1, 1901. Serial No. 66,711. (No model.)

To all whom it may concern:

Be it known that I, ROBERT LEYER, a citizen of the German Empire, residing at Gummersbach, in the Province of Rhenish Prussia, Kingdom of Prussia, Germany, have invented certain new and useful Improvements in Rectifiers for Spirit-Stills; and I do hereby declare the following to be a full, clear, and exact description of the invention, such as will enable others skilled in the art to which it appertains to make and use the same.

This invention relates to improvements in rectifiers for spirit-stills; and it has for its object to produce a better dephlegmation of the spirit-vapors and to increase the quantity of spirit obtainable from a certain amount of mash. In order to attain these objects, I have designed the new rectifier as shown on the accompanying drawings, in which—

20 Figure 1 is a vertical central section along line I I of Fig. 2. Fig. 2 is a horizontal section along line II II of Fig. 1.

The rectifier consists of a hollow cylindrical vessel 1, which is closed at the top by a cover 2. This vessel is fixed upon the still, (indicated in dotted lines in the drawings,) from

25 which the alcoholic vapors rise into the rectifier through a pipe 3, in which case the rectifier is placed immediately upon the still.

30 Inside of the vessel 1 are placed concentrically three other hollow cylinders 4, 5, and 6, respectively. These three inner cylinders are so arranged that they can be withdrawn out of the vessel 1 when the cover 2 is taken off.

35 By this arrangement three annular spaces 7, 8, and 9 are formed between the cylinders. The space 8 between the two cylinders 5 and 6 is closed at the bottom by a cover 12, and

40 the cylinders 6 and 4 are so connected together or closed at top by a cover 10 that the annular spaces 7 and 8 communicate with each other, the intermediate cylinder 5 not reaching quite up to the cover 10. The annular space 7 between the cylinders 4 and 5

45 is closed at bottom by a flange 11. The circumference or mantle of the cylinder 6 is provided with pockets or plates 13 of half-round or oval shape and projecting alternately on diametrically opposite sides to the right and to 50 the left so far that their peripheries touch for about half a circle the inner circumference of the cylinder 1, the other half leaving a free

passage between the vessel 1 and the cylinder 6, so that fluids or vapors rising between 1 and 6 are forced to make the zigzag course 55 indicated by the arrows in Fig. 1. The inner cylinder 4 has a hemispherical bottom 15, and into the space 17 inside of this is suspended from the top or cover 2 the exhaust-tube 18, which is open at the bottom and widened. 60 From this it will be seen that the vapors rising up in a serpentine line between 1, 6, and 13 pass over the cover 10 and then descend into the space 17, whence they rise up again and pass out by the tube 18. 65

The annular spaces 7 8 and the space of the pockets 13 serve to receive the cooling fluid, which may be cooling-water or fresh mash. It is introduced into said space 7 by the pipe 19, rises up therein, and passes over 70 the upper edge of the cylinder 5 into the space 8, whence it descends to escape by the pipe 20. The pipe 21, inserted at the top of the cover 10, serves for leading off air, vapor, or gas which may have gathered in the annular spaces 7 and 8. 75

It will be seen that the alcoholic vapors pass through the apparatus in the opposite direction to the cooling fluid, making thereby the long serpentine way, and over the enlarged cooling-surfaces of the pockets 13, so that water and empyreumatic substances and other detrimental matters can be deposited or separated from the pure alcohol. 80

The condensed fluid which is collected in 85 the space 17 is led back into the space 9 by the pipes 22 and 22', so that it can be reëvaporized, or it can be let off by the pipe 23, cocks or valves 22^a and 23^a being inserted, as indicated. 90

All parts of the described apparatus are so connected and jointed together that they can be easily taken asunder for inspection and cleaning.

Having thus described my invention, I declare that what I claim, and desire to secure by Letters Patent, is— 95

In a rectifier for spirit-stills, the combination of a cylindrical vessel, 1, having a cover, 2, and a suitable inlet, 3, at the bottom with a cylinder, 6, placed concentrically inside said vessel, pockets, 13, projecting from cylinder, 6, alternately on diametrically opposite sides and touching, for half the circum-

ference, the inside periphery of vessel, 1, a cylinder, 5, placed inside of cylinder, 6, and connected to the latter an annular bottom plate 12, but open at the upper end, a cylinder, 4, placed inside of cylinder, 5, and reaching up with its upper edge to the level of the edge of cylinder, 6, and being connected to this by a cover, 10, so as to leave a free passage over the edge of cylinder, 5, and between said cover, 10, a bottom flange, 11, connecting the cylinder, 4, to cylinder, 5, so as to close the annular space, 7, between these two cylinders, a hemispherical bottom, 15, closing the lower end of cylinder, 4, an exhaust tube, 18, for alcoholic vapors reaching into cylinder, 4, and passing out through the cover, 2, of vessel, 1, an inlet-pipe, 19, for cooling fluid passing through the vessel, 1, and reach-

ing into the annular space, 7, between the cylinders, 4 and 5, an outlet-pipe, 20, for leading the cooling fluid from the bottom of the annular space, 8, between the cylinders, 5 and 6, out of the apparatus and a connecting-pipe, 22, allowing useful condensed products to return into the zigzag passage between the vessel, 1, and cylinder, 6, and leading off, by a branch, 23, the empyreumatic substances and other detrimental condensed products, the whole as described and illustrated and for the purpose set forth.

In testimony whereof I have affixed my signature in presence of two witnesses.

ROBERT LEYER.
